US00D395952S

United States Patent [19]

Buczwinski et al.

[11] Patent Number: **Des. 395,952**[45] Date of Patent: ****Jul. 14, 1998**

[54] CONTAINER

[75] Inventors: **Carey Alix Buczwinski; Todd Christopher Larson; Annamaria Serbiak**, all of Appleton, Wis.; **Alfred Jack Astoreca, Annandale; Peter Anthony Piscopo**, Medford, both of N.J.; **Richard Herman Seager**, Mystic, Conn.

[73] Assignee: **Kimberly-Clark Worldwide, Inc.**, Neenah, Wis.

[**] Term: **14 Years**

[21] Appl. No.: **71,678**

[22] Filed: **Jun. 4, 1997**

[51] LOC (6) Cl. **03-01**

[52] U.S. Cl. **D3/294**

[58] Field of Search **D3/294, 272, 273, D3/295; D9/423, 424, 420, 425; 206/503, 508, 511, 518; 220/334, 335, 337, 350, 354, 355, 356**
